BOX STAYING MACHINE

Martin V. Silby, Brooklyn, N. Y.

Application February 25, 1933, Serial No. 658,508

9 Claims. (Cl. 93—56)

This invention relates to apparatus for attaching stays or reinforcing strips to the corner joints of boxes made of paper-board, paper or similar material; and has for its general object the provision of a machine for applying such stays to boxes whose outer walls are inclined convergently from the bottom upward, so that the box, or at least the base thereof, presents the form of the frustum of a solid, as for example a pyramid, 10 when stays have been provided at its several inclined upright joints.

A more particular object of the invention is to provide such a machine with means readily used and controlled by operatives having only average mechanical skill, to receive and present for the staying operations box blanks of a novel form which would present somewhat unusual difficulties to speed and accuracy of manipulation by such operatives in the absence of the improvements by which the machine of the present invention is characterized as hereinafter disclosed.

Another object of the invention is to provide such a machine with means to utilize a continuous stock strip of stay material in the operation of the machine, which is provided for that purpose with the instrumentalities requisite to support and feed such stay strip stock intermittently and to sever therefrom stay-pieces of the very special contour necessary to permit the production of neat and slightly corner reinforcements of the bevelled corner joints of the box.

Among other objects of the invention is the provision of such a machine with the operating elements so arranged as to be readily accessible for inspection, adjustment, removal and replacement, and also to provide elements of sturdy construction, cooperating smoothly and with but little wear throughout a long period of usefulness.

Still another object of the invention is to organize the various instrumentalities of such a machine in the general arrangement characteristic of machines embodying the invention of the Knowlton Patent No. 1,061,084, inasmuch as the structure and operation of such "corner stayer machines" so-called are familiar to the trade and well understood by operatives; although it is to be understood that various features of the invention are susceptible of embodiment in numerous other types of machines for analogous purposes.

The invention also has for an object a novel method of fabricating box members having convergent walls and as a cognate object a box member having novel structural features formed by said method.

The above, and other features of the invention,

are illustrated and described fully in the accompanying drawings and specification and are pointed out in the claims.

In the drawings:

Fig. 1 is a view in side elevation of the upper parts of a box-corner stay-attaching machine embodying this invention, showing in dotted lines a box-blank supported in position for a stay-attaching operation upon one corner joint thereof.

Fig. 2 is a front view of the machine.

Fig. 3 is a fragmentary sectional detail view of part of the cooperating cutting and pressing mechanism, taken upon the line 3—3 of Fig. 2.

Fig. 4 is a similar view on the line 4—4 of Fig. 3.

Fig. 5 is a view in plan of a novel box blank 15 suitable for use in carrying the invention into effect.

Fig. 6 is a plan view of a completed box base, fitted with stay strips by use of the machine.

Fig. 7 is a vertical section on the line 7—7 20 of Fig. 6.

Fig. 8 is a detail view of one of the chevron-shaped stay-pieces taken separately.

Fig. 9 is a view in perspective of a now-preferred form of a complete box embodying a base member 25 and an extension member or box proper, assembled to form a unitary structure embodying the invention.

In the now-preferred embodiment of the invention selected for illustration in the drawings, the part designated by the numeral 11 is the head-frame of the machine in which is journaled a main driving shaft 12 having a pulley 13 adapted to be driven by a belt running from a suitable source of power to operate the machine.

At the front of the machine is fitted in vertical guides 14 a reciprocating slide 15 having near its lower end a stud 16 which is connected by a connecting rod 17 to a wrist-pin 18 on the driving shaft 12, by which the shaft is arranged to cause vertical reciprocation of a die-stock 19 mounted on the lower end of slide 15.

In the die-stock 19 is secured removably, as by a set-screw 21, a member 20 comprising a cutter element 22 and a presser element 23, these elements being conveniently formed as integral parts of the member 21, as illustrated, although this is not essential.

The reference numeral 24 designates another cutter element, bolted to the frame at 25 and arranged to coact with the cutter element 22 in severing stay-pieces of appropriate shape and size from a continuous stock strip 26 of paper or other suitable tape which is fed intermittently across the path of descent of cutter element 22.

between the latter and cutter element 24, at the desired intervals, to bring into position for severance successive end-portions of the tape, which in the instance illustrated are respectively of the 5 form of a chevron as indicated at 27 in Fig. 1, and separately in detail in Fig. 8.

The cutter elements 22 and 24 are suitably shaped to produce this, or any desired and suitable shape, and their present structure is illustrated 10 in side elevation in Fig. 1 and more in detail in Figs. 3 and 4.

The stock strip of tape 26 may be, and preferably is, for the present purpose, given an inverted V-shaped contour in cross-section, as indicated 15 at the broken-off rear portion thereof toward the right-hand side of Fig. 1, either before, or during, its passage through a guide-roll couple 28, one of the rolls preferably dipping into a tank 29 of water or adhesive, to permit the under surface of the tape to be moistened, if it is already provided with adhesive, or to apply adhesive thereto if desired.

Any suitable step-by-step feeding mechanism 25 may be utilized to feed the tape, and as one convenient and preferred form of such feeding mechanism I have illustrated a cross-head 30 sliding in guides 31 and provided with a pair of jaws 32, 33, of which the former is fast upon the head, while the latter is mounted upon one arm of a 30 bell-crank lever 34, the other arm of which is connected by a link 35 to a pitman 36 journaled upon a pin 37 at the top of the frame 11.

A spring 38 tends to draw the pitman rearwardly, and with it the head 30 and jaws 32, 33, 35 at the same time causing the upper jaw to recede from gripping engagement with the tape, in obvious fashion, due to the lag of the head under frictional engagement with the slideway 31, and/or the auxiliary action of a spring 39 mounted 40 on a bracket 40 which may also serve as an abutment or stop to limit rearward pivotal motion of the bell-crank lever under the action of link 35 and spring 39.

Forward feeding movement of the pitman 36 45 and tape 26 is caused by the action of a face cam 41 mounted to rotate with the shaft 12 and bearing against an anti-friction roller 42 upon the pitman, the jaw 33 being clamped downward upon the jaw 32 and intervening portion of the 50 tape 26 when the link 35 is pushed forwardly by the pitman. The throw of pitman 36 may be regulated by means of a screw 43 to vary the extent of feeding movement of the head 30.

Passing now to the novel stay-applying mechanism proper, this comprises, in its now-preferred form, a box supporting member 44 adapted to be moved into position to support the box-blank B in juxtaposition with the cutter elements 22, 24, already described, and with the reciprocating presser element 23 associated with the movable cutter element, so that each chevron-shaped stay-portion 27 severed from the stock-strip 26 will be received by an appropriate corner joint of the box, in a manner to be described more 65 at length, and then the box-support will be removed bodily to a position remote from the region of stay-application, so that the box can be readily manipulated by the operative to arrange another corner joint in stay-attaching position, and 70 so that the operative can readily remove the box when it has received its full complement of stay-strips, and a fresh box-blank can be quickly substituted therefor.

To accomplish the above aim, the box-support 75 44 preferably takes the form, as illustrated, of an

inverted V-shaped anvil or pressure-resisting member, mounted to reciprocate horizontally in a guideway 45 mounted upon a bracket 46 bolted at 47 to the frame 11, and this reciprocation is accomplished yieldingly in the forward direction by a tension spring 46' connected at 47' to the rear end of the anvil, and connected at 48 to the stationary guideway.

Retractive movement of the box-supporting anvil is accomplished positively by a pitman 49, 10 swinging from a rock-shaft 50 supported by brackets 51 upon the frame 11, and actuated by a cam 52 mounted upon the vertically sliding head 15, so arranged that when the slide 15 moves upward, the box-support 44 is moved positively outward, by the action of an anti-friction roller 53 carried in a fork 54 at the lower end of pitman 49 and working in a yoke 55 extending upward from the member 44 and which permits compensating action between the arcuate movement of the roller 53 and the right-line movement of the member 44.

It will be observed that by thus providing for a considerable range of bodily movement by the box-supporting member 44, ample free space is 25 yielded for easy and accurate manipulation of the box-blank B by the operative, who has only to place the box-blank B against a gauge plate 56 mounted on a frame bracket 57 (see Fig. 3), which is preferably inclined downwardly and outwardly 30 to provide sufficient clearance for such manipulation. The gauge plate has wings 60, in inverted V-shaped relation, to limit the upward movement of the box-blank. The above-mentioned clearance is further provided for by arranging the box-supporting member to slide rearwardly, under actuation by the pitman 49, to an extent clearly indicated in Fig. 1, where the nose 58 of the anvil appears in its retracted position, this nose portion being cut away at its under side 59. The importance of this novel arrangement will be realized when it is considered that provision is being made for the attachment of chevron-shaped stay-pieces 27 to bevelled corner joints b^1 between convergently tapering walls b^2 of the box-blanks B (see 45 Figs. 5-7), and it is to be added that the problem of so providing for novel treatment of the box-blanks was further complicated by the practical necessity of utilizing box-blanks of highly 50 specialized structure.

This becomes more apparent upon reference to Fig. 7, in which is shown clearly the presence of re-entrant box-wall portions or flaps b^3 , which I have provided to render more stable the structure of the box walls, and which aid the operative in preparing the box-blanks to receive the nose 58 of the anvil, a simple folding movement of each flap b^3 sufficing to effect this preparation. The 55 blanks, as shown in Fig. 5, are preferably scored along the lines b^4 and b^5 to facilitate accurate folding of the flaps, and of the bottom joints where the walls are hinged to the bottom of the box.

It is also to be noted that the box-blanks are applied to the gauge plate 56 with the box opening outwardly, instead of inwardly, in order to receive the anvil nose 58, and thus constitutes a departure from conventional practice in the 60 operation of such machines.

The attaching operation is automatically completed by the machine, without the need for further manipulation by the operative other than the slight effort involved in holding the blank snugly in place up against the gauge plate 56, as the anvil 44 moves forward under the yielding 75

pressure of the spring 46, inasmuch as the action of the member 44 is such as to support the convergently abutting wall-edges at the corner joint, and to press the blank lightly but firmly against the gauge wings 60, while the presser element 23 descends to seat itself against the bevelled corner joint of the box blank, with the chevron-shaped stay-piece 27 held firmly therebetween.

The stay-piece, already provided on its under surface as hereinbefore described, is thus attached firmly and accurately in place and the attachment of one corner stay having thus been completed, the continued actuation of the machine automatically through the inoperative phases of its cycle acts to raise the associated reciprocating cutter and presser elements 22 and 23 away from the box corner, and then to retract the box-support 44 positively, to bring its nose 58 to the position shown in Fig. 1, without any reliance upon the personal initiative of the operative, who has only to shift the box-blank to adjust a fresh corner joint into position against the gauge 56, or to remove the blank and substitute a new blank, as the case may be.

Ample time is allowed for these simple manual operations, and there is no danger of injury to stock or to the operative if any given corner joint treatment happens to fail, as the inward movement is a yielding one, dependent upon the tension of spring 46, which need not be of sufficient strength to endanger the operative or the stock.

The completed product, when it has the shape shown in Fig. 6, which, of course, is merely an illustrative form, constitutes a shallow box structure with converging walls having bevelled corner joints firmly held by the stay pieces, which are neat in appearance, owing to the novel chevron shape, which insures a perfect parallelism of the upper and lower edges of the stay pieces relatively to each other and to the plane of the box bottom.

Such a shallow box member is particularly useful to impart a graceful base finish to conventional strength sided boxes, in the manner illustrated in Fig. 9, where the reference character B' designates the conventional cubical box, with the base of Fig. 6 applied thereto.

It will be understood, without further illustration, that the composite product shown in Fig. 9 can be covered with a paper facing of ornamental or any desired and suitable design, and that the box B' can be provided with a cover of conventional form, or one taking the form of the shallow box member of Fig. 6, if it be desired to carry out a symmetrical embodiment of the invention at the top and bottom of the box.

The bottom member and/or the top member, if such is provided, can be attached permanently to the box B', or either or both of such members can be associated removably therewith, the frictional effect of the flaps b³ being sufficient to insure retention of the member of Fig. 6 in place upon the box B', if the material of the blank B is sufficiently stiff.

I claim:

1. In a machine for attaching box-corner stays, the combination with a frame, of a reciprocating plunger and operating means therefor mounted on said frame, a stay-cutter and a stay-pressing means respectively movable with, and actuated by, said plunger, a cooperating stay-cutter mounted on said frame, a gauge, and a combined box-support and auxiliary presser means also mounted upon said frame and adapted to be moved into position to support said box in juxtaposition with the exterior corner-joint-wall portions of a box,

said gauge, cutter devices and movable pressing device, to receive a stay, said box-support being movable bodily away from the operating path of said reciprocating cutter and presser devices to permit respectively the application of a box to said gauge, and removal therefrom of said box when it has received said stay.

2. In a machine for attaching box-corner stays, the combination with a frame, of a reciprocating plunger and operating means therefor mounted on said frame, a stay-cutter and a stay-pressing means respectively movable with, and actuated by, said plunger, a cooperating stay-cutter mounted on said frame, a gauge, and a combined box-support and auxiliary presser means also mounted upon said frame and adapted to be moved into position to engage said box, and to support said box and press it against said gauge, in juxtaposition with said cutter device and pressing devices, to receive a stay, said box-support being movable bodily away from the operating path of said reciprocating cutter and presser devices to permit respectively the application of a box to said gauge, the adjustment of said box corner for corner, on said gauge without complete removal therefrom, and the final removal therefrom of said box when it has received said stay.

3. In a machine for attaching box-corner stays, the combination with a frame, of a reciprocating plunger and operating means therefor mounted on said frame, a stay-cutter and a stay-pressing means respectively movable with, and actuated by, said plunger, a cooperating stay-cutter mounted on said frame, a gauge, and a combined box-support and cooperating presser anvil also mounted upon said frame and adapted to be moved into position to support said box in juxtaposition with said gauge, cutter device and pressing devices, to receive a stay, said box-support being movable bodily away from the operating path of said reciprocating cutter and presser devices to leave a free space of substantial extent between said path and said anvil, thereby to permit complete operative manipulation of said box without removal thereof from said gauge, and to permit respectively the application of a box to said gauge, and removal therefrom of said box when it has received said stay.

4. In a machine for attaching box-corner stays, the combination with a frame, of a reciprocating plunger and operating means therefor mounted on said frame, a stay-cutter and a stay-pressing means respectively movable with, and actuated by, said plunger, a cooperating stay-cutter mounted on said frame, a gauge, and a combined box-support and presser anvil means also mounted upon said frame and adapted to be moved into position to support said box in juxtaposition with said gauge, cutter devices and movable pressing device, to receive a stay, said box-support being supported on a slide mounted in a slideway remote from the operating path of said cutter and presser devices and adapted to permit respectively the application of a box to said gauge, and removal therefrom of said box when it has received said stay, and means tending to urge said box-support yieldingly into position to engage said box and support it in position to receive said stay, and means to move said support positively away from said position.

5. In a machine for attaching box-corner stays, cutting devices adapted to sever successive stay parts from a stock strip thereof, and presser devices adapted to apply said stay parts seriatim to the exterior corner-joint-wall portions of a box,

- a gauge, and a box-support movable relatively to the path of stay-applying operation of said presser devices, said support being adapted to enter the box and to press said box bottom-end forward toward said gauge, said box-support being retractable from said path bodily to a position suitable to permit free manipulation of said box without complete removal of said box from said gauge.
10. 6. A machine for attaching box-corner stays to the bevelled corners of a box having at least a portion of its exterior contour in the shape of the frustum of a solid, for example, the frustum of a pyramid, said machine comprising means to present stay-parts of suitable contour successively in position for application to said bevelled box corners, and movable means to press said stay parts successively upon said box corners, and a box-support movable bodily toward and away from the path of operative movement of said presser means, said support including a presser anvil having a nose portion to enter said box, and support an inner portion of the box walls, the under portion of said nose being bevelled rearwardly from the tip of the nose to afford clearance for the box when withdrawn from the path of operative movement of said presser devices.

whereby the box may be manipulated readily to present its exterior stay-receiving wall in parallelism with said stay-pressing devices.

7. In a machine of the class described, means to feed a V-shaped stock strip of stay material, and means to sever therefrom successive approximately chevron-shaped stay-pieces.

8. A machine according to claim 6, and further characterized by having means to feed intermittently a stock strip of stay material, and means to sever therefrom successive approximately chevron-shaped stay parts, in position respectively to be applied to said bevelled box corners by said presser means.

9. In an apparatus for staying the corner sections of a box having inwardly inclined side portions, the combination of a retractable member shaped to fit the recess formed by the corner section and means for moving said member into the corner section, a pair of dies for cutting a gummed stay to the desired shape, one of said dies having a surface shaped to fit the exterior of the corner section and adapted to press the gummed stay into engagement with the corner section.

MARTIN V. SILBY.
